UNITED STATES PATENT OFFICE.

CANDACE WHEELER, OF JAMAICA, NEW YORK.

ART OF EMBROIDERING AND EMBROIDERY.

SPECIFICATION forming part of Letters Patent No. 268,332, dated November 28, 1882.

Application filed July 20, 1881. (Model.) Patented in England March 14, 1882, No. 1,233.

To all whom it may concern:

Be it known that I, CANDACE WHEELER, of Jamaica, Long Island, in the county of Queens and State of New York, have invented a new and useful Improvement in the Art of Embroidering, of which the following is a full, clear, and exact description.

The object of this invention is to provide a new method of embroidering, by which tapestry or picture effects may be produced; and the invention consists in passing the embroidery-threads under the warp and over the woof of the fabric, thereby covering the woof with the embroidery-threads, whereby the latter will be held in place by the crossing threads of the fabric, thus imitating the surface of the woven fabric, so far as relates to the form of its threads, while producing the color and form of the picture or design. The design or picture to be produced is preferably first traced or drawn upon the fabric.

In the accompanying drawings, Figure 1 represents a plan of a fabric with the picture or design wrought thereon with colored threads, the threads of the fabric and woven covering being much enlarged. The fabric shown in Fig. 1 is a single ply. Fig. 2 shows in plan, and Figs. 3, 4, and 5 in sections, two-ply or special fabric which is preferably used for this work.

In Figs. 2, 4, and 5 the ornamental threads which constitute the design are indicated by heavy black line. The sections show respectively in Fig. 3 the fabric as cut upon the straight or central warp-thread, B². The serpentine or binding warp-threads B and B', which are indicated in dotted lines in this figure, hold the woof-thread C of the face and C' of the back against the warp-thread B², and bind the whole fabric together. The woof-threads C of the face are smaller than the woof-threads C' of the back of the fabric, and when the ornamental threads F are introduced they occupy the position indicated in Figs. 2, 4, and 5, passing under the loops of the binding warp-threads B and B', where they cross the woof-threads C' of the face, and to a greater or less extent cover the threads C, so that the threads F are apparently woven into the fabric, and

by their difference in color from the loom-woven woof-thread produce the pictured design.

In Fig. 1, which represents the invention as worked upon a single-ply fabric, A represents the fabric. B represents the warp, and C the woof. F F represents the colored embroidery-threads following or covering the woof C.

In the operation in this instance the threaded needle is passed up through the fabric A at the points where it is designed that the embroidery-threads F should begin to overlie the woof C. Then the needle, drawing the embroidery-threads F after it, is passed along the woof C beneath each successive warp-thread B to make single stitches, or beneath every other thread B for double stitches; and at the termination of the woof-thread thus covered the threaded needle is passed down again through the fabric A and the embroidery-thread there fastened; or the said needle is turned about and passed in an opposite and parallel direction along the next woof-thread C beneath the warp-threads B, as set forth, and thus the work is continued until the design is complete, the different-colored threads being thus introduced or interwoven, as may be required, for the desired effect. These threads F F may be applied in long or double stitches, as shown at a, in short or single stitches, as shown at b, or in stitches of any length that are best calculated to produce the desired effects. Excepting where the embroidery-stitches are begun and ended, they are superficial—that is to say, they do not pass through the fabric like ordinary embroidery-stitches, but cover only the woof C, being woven in and out through or under the warp B.

I am aware that tapestries have been embroidered by inserting ornamental threads in spaces between the woven woof-threads of the fabric, such threads being held by the warp-threads under the woof-threads, where they appear in the interstices between the woof-threads. Such embroideries or needle-woven tapestries I do not claim; but,

Having thus described my invention, I claim as new and desire to secure by Letters Patent—

1. The method of embroidering woven fab-

ries which consists in carrying with a needle ornamental threads longitudinally over the woof and under some of the crossing threads, but not through the fabric, except at the ends of the threads, where they are fastened, substantially as described.

2. An embroidered fabric having the woof threads covered longitudinally by ornamental

threads, which are held in place by the crossing threads of the fabric and passed through to the fabric only at the ends, where they are fastened, substantially as described.

CANDACE WHEELER.
